ABSTRACT: A contact sensor adapted to be engaged by traveling articles of electrically conducting material includes a tube of such material set in a grounded metal post and projecting therefrom so as to ensure such engagement. A sleeve of electrically insulating material secured in the tube extends outwardly beyond the end thereof opposite that which the articles approach. A spring-extended plunger anchored to sleeve has a head extending into the path of the articles for engagement thereby. A through bolt secures the plunger to the sleeve and slides in a cap of insulating material secured over the end of the sleeve. The head is grounded on engagement by an approaching article and a circuit through the bolt is completed to energize a control relay or contactor.

**CONTACT SENSOR ADAPTED TO BE ENGAGED BY
TRAVELING ARTICLES OF ELECTRICALLY
CONDUCTING MATERIAL**

This invention relates to a contact sensor and, in particular, to a sensor adapted to signal the presence of large massive articles traveling on a conveyor.

BACKGROUND OF THE INVENTION

It has been the practice heretofore to provide conveyors for large massive articles with a limit switch engageable thereby, effective to close a control circuit, e.g., to stop the conveyor on arrival of the articles at a point where removal thereof from the conveyor is necessary. An example is the conveyor employed for moving coils of steel strip on end from a hot-rolling mill to a cold-rolling mill. The limit switches used, because of their fragile construction, were subject to damage by the contact of the coils therewith, necessitating frequent maintenance work and excessive amounts of "down time." The object of my invention is to provide an improved contact sensor of simple and sturdy construction, well adapted to withstand heavy impact or shock load and effective instantaneously to give the desired control signal.

The most pertinent prior art known to me is Brickner, U.S. Pat. No. 2,090,178.

SUMMARY OF THE INVENTION

My improved contact sensor comprises essentially an upstanding grounded post or other support of electrically conducting material. A tube of such material in electrically conducting relation with the post extends generally horizontally therefrom in a direction opposite that in which the articles travel and into the path thereof. A sleeve of electrically insulating material is fitted in the tube and extends beyond the rear end thereof slightly, i.e., the end opposite that adapted to be engaged by the articles. A spring-extended plunger is anchored in the sleeve and has a head at its forward end suitable for engagement by the articles. A cap of insulating material is fitted on the rear end of the sleeve and a through bolt of conducting material extends from the head through the cap. Thus, when an article of electrically conducting material, grounded on a conveyor, strikes the head of the plunger, a circuit is completed including a conductor attached to the bolt, a relay or contactor and a current source having one terminal grounded. Energization of the relay may serve to stop the conveyor or perform some other desired function.

BRIEF DESCRIPTION OF THE DRAWINGS

A complete understanding of the invention may be obtained from the following detailed description and explanation which refer to the accompanying drawings illustrating the present preferred embodiment. In the drawings:

FIG. 1 is a partial plan view showing a coil of strip on a conveyor, in arrested position against stop posts fitted with my sensor;

FIG. 2 is an elevation thereof;

FIG. 3 is a section to enlarged scale, taken on the plane of line III-III of FIG. 2; and

FIG. 4 is an elementary circuit diagram.

**DETAILED DESCRIPTION OF THE PREFERRED
EMBODIMENT**

Referring now in detail to the drawings, and for the present, particularly to FIGS. 1 and 2, a conveyor 10 of any suitable construction (that shown being of the roller type) serves to move coils 11 along a predetermined path. Stop posts 12 upstanding from the conveyor arrest each coil as it reaches the limit of its travel. The posts are fitted with one or more sensors 13, one of which is shown in detail in FIG. 3. Referring now to

the latter, posts 12 of steel or other electrical conductor are grounded on the conveyor frame (not shown) and are drilled to receive tubes 14 of conducting metal, secured in such position and at such an angle as to be in the path of an article approaching the posts on conveyor 10.

A sleeve 15 of electrically insulating material fits snugly in tube 14 and extends a short distance beyond the end thereof away from articles approaching on conveyor 10. A cap 29 of electrically insulating material is threaded on the projecting end of sleeve 15. A plunger 16 including forward and rear cylinders 17 and 18 with a compression spring 19 therebetween, is slidable in sleeve 15. Cylinder 17 has a diaphragm disc 20 fixed therein and a ball-head attachment 21 is fitted in the forward end of the cylinder. A through bolt 22 secured to the diaphragm extends through the cylinders 17 and 18, spring 19 and cap 29. Nuts 23 threaded on the projecting end of the bolt anchor the plunger in the sleeve. A spacer tube 24 is seated in cylinder 18 behind spring 19. A set screw 25 threaded radially through tube 14 engages sleeve 15 to hold it in place.

It will be evident from the foregoing that plunger 16 and its ball-head attachment 21 are completely insulated from the supporting post 12. Thus, a simple circuit shown in FIG. 4 from bolt 22 through a contactor coil 26 to a current source 27 will be completed on engagement of the attachment 21 by an article of electrically conducting material on the conveyor, if the other terminal of the source be grounded as shown. Operation of the contactor will open the circuit to the motor 28 driving the conveyor.

30 It is apparent from the foregoing description that my invention provides a contact sensor for electrically conducting articles characterized by simplicity, sturdiness and quick operation. No movement of the article beyond initial contact is needed to complete the contactor-energizing circuit. The construction of the device is such as practically to eliminate maintenance altogether.

I claim:

1. A contact sensor adapted to be actuated by engagement of traveling electrically conducting articles therewith comprising a tube of electrically conducting metal, a grounded post of electrically conducting metal in conducting relation with and supporting said tube so that one end of said tube is directed toward and terminating short of the outer surface of said post in the path of an approaching article, a sleeve of electrically insulating material telescoped into said tube with one end of said sleeve projecting from the end of said tube opposite said one end of said tube, a telescoping spring-extended plunger slidably disposed in said sleeve with one end thereof projecting from the end of said sleeve opposite said projecting end of said sleeve so as to be engageable by and forced into said sleeve when engaged by an approaching article, a cap of insulating material secured on said projecting end of said sleeve, a portion of said plunger extending substantially from one end to the other end of said sleeve and projecting slidably through said cap, and stop means on said portion of said plunger adapted to engage said cap to limit the extension of said plunger toward an approaching article.

2. Apparatus as defined by claim 1 characterized by said plunger including a through bolt extending slidably through 60 said sleeve and said cap, and article-engaging means fixed on the end of said bolt opposite the end thereof projecting through said cap.

3. Apparatus as defined by claim 2 in which said article-engaging means includes a cylinder integral with and surrounding the end of said bolt opposite from said cap, said cylinder being slidable in said sleeve, and the ball head disposed in said cylinder with a portion thereof normally projecting from the end of said sleeve remote from said cap.
